UNITED STATES PATENT OFFICE.

JOSEPH FISCHER, OF NEW YORK, N. Y.

DESIGN FOR A FINGER-RING.

SPECIFICATION forming part of Design No. 24,194, dated April 16, 1895.

Application filed March 4, 1895. Serial No. 540,536. Term of patent 14 years.

To all whom it may concern:

Be it known that I, JOSEPH FISCHER, a subject of the Emperor of Austria-Hungary, residing at New York, in the county of New York and State of New York, have invented and produced a new and original Design for a Finger-Ring, of which the following is a specification, reference being had to the accompanying drawings.

10 My design relates to finger rings and is well shown in the accompanying drawings, wherein—

Figure 1, is a top or plan view; Fig. 2, an edge view, and Fig. 3 a side elevation.

15 Similar letters of reference indicate corresponding parts in all the figures.

A is the band, and B the principal central crown carrying a stone or setting, a. As will be observed, the crown is well raised and its 20 sides more than ordinarily steep. The crown is joined with the band on each side by graceful curves, openings, as b b, being left to give

an appearance of lightness. Upon the unions of crown and band on each side, are panels, c c, the branches of which are arranged at 25 about right angles with each other. The apex at the tops and these panels are supplied with stones or settings, d d, smaller than the one in the crown. The stones or settings are of any character or color and may be varied to 30 suit the taste. The panels and crown thus united afford an ornamental and artistic design and contribute brilliancy to the ring with comparatively little expense for the settings.

Having now fully described my design, what 35 I claim as new, and desire to secure by Letters Patent, is—

The design for a finger ring substantially as herein shown and set forth.

JOSEPH FISCHER.
